UNITED STATES PATENT OFFICE.

JOHN HENRY EWART, OF LONDON, ENGLAND.

ELECTRIC WATER HEATER.

Application filed July 7, 1926, Serial No. 121,026, and in Great Britain January 12, 1926.

This invention relates to improvements in electric water-heaters or geysers and in heating elements therefor.

According to the invention the heater

5 comprises a water tank having at its lower portion thereof sockets for the attachment of an electric heating element at suitable intervals, the said heating elements each comprising a conductor wire wound on a former carrying plugs or terminals for insertion in the sockets provided on the lower portion of the heater body so that it is possible readily to remove the individual elements from the heater body when desired.

15 In a suitable arrangement according to the invention the heater comprises a cylindrical or other form of tank with the usual inlet and outlet pipes. Socket terminals are carried by an insulating base fixed at the 20 bottom of the said tank and are connected to the main current supply. The heating elements each comprises a conductor or resistance wire wound on a former having connected thereto plugs, with which the ends 25 of the conductor wire are in connection, for insertion in the aforesaid sockets carried by the base. The heating elements are held in position in the tank by means of upright tubular guides into which the said elements 30 are inserted.

In a modified form of construction of heater element the top thereof may be provided with terminals which make electrical connection with the conductor or resistance 35 wire so that, if desired, it may be possible to insert a second series or tier upon the first, in which case the conductor wires may be in series with one another, or may be connected in parallel as desired. It will be understood that I may employ any number of 40 heating elements side by side or any number of tiers of elements.

To enable the invention to be fully understood I will describe it by reference to the 45 accompanying drawing, in which:—

Figure 1 is a sectional elevation of an electric water-heater constructed in accordance with the invention.

Figures 2, 3 and 4, are, respectively, sections on the lines 2—2, 3—3 and 4—4, Figure 1.

Figure 5 is a sectional elevation of one of the electric heating elements detached and

drawn to a larger scale than Figures 1 to 4.

Figures 6 and 7 are, respectively, a plan view and an underside view of the said element.

a is the tank having the inlet pipe *b* for the cold water and the outlet pipe *c* for the water after being heated, the latter pipe being shown in the form of a spiral. The bottom of the tank is formed by the base *d*, which has socket terminals *e*, *e* to receive plugs on the current supply leads, not shown, *f*, *f* are the tubular guides within the tank *a* for the heating elements, the said guides being mounted upon and being open to the base *d* and extending through perforated baffles *g*, *g* arranged transversely of the tank *a*.

h, *i* are the socket terminals carried by the base and connected to the terminals *e*, *e* as hereinafter described, the said sockets being directly carried by a slab of insulating material *j*.

k is the conductor or resistance wire of each heating element and *l* is the former on which the said wire is wound, *m*, *n* being socket terminals carried by one end of the said former with which the two ends of the wire *k* are in electrical connection, one end of the said wire being directly connected to the socket *m* whilst the other end of the said wire is connected directly to a metal fitting *o* carried at the other end of the former *l* and which is in electrical connection with the socket *n* by the insulated wire *o*. *p*, *q* are the plugs which engage, respectively, with the sockets *m*, *n* and with the sockets *h*, *i*.

In order that the heating elements can be arranged in tiers, the ends thereof remote from those carrying the terminals *m*, *n* are provided with plug terminals *r*, *s* the latter being formed on, or attached to, the fittings *o* whilst the former are in electrical connection with the terminals *m* by the insulated wire *t*.

By this arrangement it will be seen that the socket terminals *m*, *n* of one heating element can be engaged with the plug terminals *r*, *s* of another heating element so that in the case of two tiers of heating elements arranged in this manner, as shown in the drawing, the current supply from the main leads for the upper tier will flow by way of

the wires o^1 and t , the circuit for the two tiers thus being in parallel. It is to be understood, however, that the wires h may be connected to the terminals of the formers l 5 so as to be in series.

In the drawings, I have shown two tiers of eight heating elements each, divided into two groups connected in parallel, one set of terminals h of one group being connected by 10 the wire u to one of the main sockets e whilst the other set of terminals i of the said group are connected by the wire v to one set of terminals h of the other group, the other set of terminals i of which are connected by 15 the wire w to the other main socket e .

The exposed plug terminals r and s , Figure 1, of the upper tier of heating elements are shown in engagement with blocks r^1 of insulating material to prevent them making 20 contact with the ends of the tubular guides f .

Although I have illustrated the heater as provided with two tiers of heating elements it is to be understood that one only or more than two tiers may be employed.

25 The base d is closed at the bottom by a slab x of insulating material supported by a metal tray y secured in position by screws z , so that it will be necessary, when placing the heating elements in position in the 30 tubular guides f , or removing them therefrom, to remove the said slab x and to detach the plugs p from the sockets h, m and the plugs q from the sockets i, n .

In practice, it may be advantageous to 35 surround the water tank with a lagging of wood or other non-conducting material for preventing the escape of heat.

When it is desired that the heater should 40 be used for producing boiling water, it will be advantageous to cause the water to proceed in a spiral or circuitous course in order to allow it to obtain as much heat as possible from the elements before reaching the outlet pipe, that is to say, the water may be led 45 into the heater from the top and allowed to flow spirally or circuitously down the one element and up the next and so on.

From the above description it will be understood that my invention permits of the 50 manufacture of stock size heater bodies, as apart from the heating elements, and permits of the ready replacement of broken elements, which can be effected by the user 55 without disturbing the water connections to the heater body.

It is also possible for the manufacturers to stock standard size elements of standard voltages which has not hitherto been possible.

60 Having now particularly described and

ascertained the nature of my said invention and in what manner the same is to be performed I declare that what I claim is:—

1. An electrically heated water-heater comprising a tank, a plurality of upright tubular guides secured to the bottom of the tank and extending within the latter, the said guides being closed at their upper ends and open at their lower ends to the exterior of the tank, heating elements within the tubular guides, each comprising a conductor of resistance wire wound on a former, fixed inverted socket terminals beneath the tank for the supply of current to the heating elements and detachable plug terminals at the lower ends of the heating elements for insertion in the said sockets as the said elements are raised to place them in position in the tubular guides.

2. An electrically heated water-heater comprising a tank, a plurality of upright tubular guides secured to the bottom of the tank and extending within the latter, the said guides being closed at their upper ends and open at their lower ends to the exterior of the tank, heating elements within the tubular guides each comprising a conductor of resistance wire wound on a former, fixed inverted socket terminals beneath the tank for the supply of current for the heating elements, socket terminals at the lower ends of the heating elements for the heating wire and plug terminals fitting within the latter socket terminals for insertion into the inverted socket terminals as the said elements are raised to place them in position in the tubular guides.

3. A water-heater as claimed in claim 2, wherein each heating element has a set of plug terminals at the end opposite to that carrying the detachable plug terminals and in electrical connection with the latter through the medium of the resistance conductor, and adapted to engage with the socket terminals on the lower end of another similar heating element, whereby the said elements are connected in series with each other.

4. A water-heater as claimed in claim 2, wherein each heating element has a set of plug terminals at the end opposite to that carrying the detachable plug terminals, in electrical connection with the latter, other than by way of the resistance wire, and adapted to engage with the socket terminals on the lower end of another similar heating element, whereby the said elements are connected in parallel.

JOHN HENRY EWART.
